CUMULATIVE-VOTING MECHANISM FOR VOTING-MACHINES.

1,072,962.

Specification of Letters Patent.

Patented Sept. 9, 1913.

Application filed August 13, 1908. Serial No. 448,432.

To all whom it may concern:

Be it known that I, WILLIAM J. LAUSTERER, a citizen of the United States, residing at Jamestown, in the county of Chautauqua and State of New York, have invented certain new and useful Improvements in Cumulative-Voting Mechanism for Voting-Machines, of which the following is a specification.

10 My present invention relates to that class of voting machines described in my former Patents Nos. 793,666 and 820,802.

It has for its object to provide a special interlock for such a machine so that said 15 machine can be adapted for use in elections where cumulative voting is practised, as is the case for example in the State of Illinois in the election of members in the general assembly thereof.

20 In the State of Illinois the constitution at present provides that three representatives shall be elected to the general assembly from each senatorial district, and that in the election of the representatives, which occurs 25 every two years, each qualified voter may cast as many votes for one candidate as there are representatives to be elected, or may distribute the same or equal parts thereof among the candidates as he shall see fit, 30 and the three candidates highest in votes shall be declared elected. Thus, the candidates Smith, Brown and Jones may be nominated by one party. The voter may at his 35 option cast three votes for Smith alone, two votes for Smith and one vote for Brown, one and a half votes for Smith and Brown each, or one vote apiece for each Smith, Brown and Jones, or may cumulate them on any one other candidate or combination of 40 candidates that he may see fit. It is the practice of the political parties in that State, where the senatorial district contains but a small majority for either party, for the two leading parties to nominate two candidates 45 only, so that the voter in voting a straight ticket may count one and a half votes for each of these candidates, although he may at his option vote otherwise, as above indicated. In other instances the party nominates but a single candidate, so that from 50 the voter who votes a straight ticket such candidate will receive three votes, while in other cases each or all the parties will

nominate two candidates for this office, but in any case the voter is entitled to and must be permitted to bunch or distribute his vote to the extent above indicated.

In order to arrange the machine to permit voters to vote in all the ways that they are entitled to vote, I have arranged the names of the candidates on the keyboard of the machine in a special way repeating them, as may be necessary and specially interlocking the keys belonging to such candidates, and disconnecting a portion of the keys from the straight ticket voting mechanism so as to allow the keys to be voted in ways as to secure all the rights above described.

This invention is also capable of use for other purposes, and it consists in certain improvements and combinations of parts hereinafter fully described, the novel features being pointed out in the claims at the end of this specification.

In the accompanying drawings Figure 1 is a front elevation of that portion of the keyboard of the machine on which the assembly ticket is placed in an Illinois election. Fig. 2 is a plan view of the interlocking channel showing the arrangement of grouping pins and compensators therein as would be necessary according to my invention for the ticket as shown in Fig. 1. Fig. 3 is an elevation of the cumulative vote lock-out as viewed from the front of the machine in Fig. 4. Fig. 4 is a sectional elevation taken transversely through all of the interlocking mechanism of the assembly group. Fig. 5 is a detail view in perspective of one of the plates for locking the sub-groups. Fig. 6 is a detail in perspective of a pair of the interlocking wedges and a compensator therefor. Fig. 7 is a detail in perspective of one of the wedges for controlling the locking plates shown in Fig. 5. Fig. 8 is a rear elevation of the keyboard of the machine, showing the connections between individual pointers and the straight ticket mechanism, by which connections an office line of keys can be connected to or disconnected from the party levers. Fig. 9 is a cross section of the line 9*, 9*, in Fig. 8. Fig. 10 is a detail in perspective of the connections at the bottom of one of the office lines in Fig. 8. Fig. 11 is a detail showing special connection between the individual

ual pointers and the party lever by which they may be driven. Fig. 12 is a detail of the compensator.

In the accompanying drawings, like reference numerals refer to like parts.

In Fig. 1 of the drawings I have shown the assembly ticket as it may occur in an Illinois election, arranged on the machine in the manner that may be necessary for the purpose of permitting the voter to vote according to his rights as above set forth. The first office line of the group in this case occurs on the seventh office line of the machine. It will be understood that there is on the machine in this instance ahead of this assembly ticket six other office lines of candidates such as governor, lieutenant-governor, secretary of state, etc. All of these offices come in a sequence that is prescribed by law. Some of these offices occur on the ticket on successive elections more frequently than others and because of this the position of the assembly ticket on the machine may vary from one election to another.

As shown in Fig. 1 the seventh office line contains the straight ticket vote, so to speak; that is, that part of the vote that will be cast by the operation of the party levers, and here it may be observed that the keys in the seventh office line in this instance are connected up so as to be operated by their respective party levers while the keys in the remaining office lines of the assembly group are disconnected from their party levers so as not to be operated or affected thereby. This will be more fully explained later on. As will be noticed in Fig. 1 in the first party row in the seventh office line, the names of two candidates are given and the ballot indicates that a vote cast by the key 7^a will count as one and a half votes for each of such candidates, that is to say, if the counter 7^a stands at the beginning of the election at 000, and at the end of the election it shows 202, the election officers will credit to each of these candidates 303 votes, the correct number of votes for each candidate being ascertained by multiplying the record of the counters by the factor shown on the ballot label, which in this case is 1½.

At 7^b three candidates' names are shown on the ballot label, and if the counter 7^b at the end of the election shows 202, then 202 will be credited to each of these three candidates by the election officers, the record of the counter in that case being multiplied by the factor, which for each of these candidates is 1.

The key 7^c belongs to but one candidate printed on the ballot label thereunder, and a vote given by the key 7^c will in that case indicate three votes for that one candidate, so that at the end of the election if the counter 7^c shows 202 votes, the correct vote to be credited by the election officers will be 606

votes, that being determined by multiplying 202 by the factor shown on the ballot label, which in this case is 3.

In the nomination of candidates for the office of assembly, it is customary for parties to nominate for this office one, two, or three candidates as it may see fit, and the names of such candidates will be printed on the ballot as part of the party straight ticket. Where paper ballots are used, each of these names will appear upon the ballot but once, and ordinarily the ballot will be printed with the proper factor in connection with each name, as designated by the party convention in the number of nominations that it makes for that office, so that the election officers in the absence of other marks on the ballot will count a straight ticket vote for that party accordingly for that office.

If the voter wishes to vote a scratch ticket when using a paper ballot, he can put such pencil marks thereon as may be necessary to properly indicate his choice, or the distribution of his votes among the various candidates, and the ballot will be counted accordingly. Such a marking on the machine, however, is not possible for each voter, because no separate record of each man's ballot is kept to be audited later by the election officers, so that it is necessary that the machine must anticipate the wants of all of the voters and must provide in advance the mechanical facilities whereby each man may exercise the choice which the law allows to him. Accordingly, twelve additional office lines of keys are used on the machine to permit the voter to vote combinations other than that provided for on the straight ticket vote. Six office lines are used to permit the voter to vote one vote for each candidate, and as shown in office lines from 8 to 13 inclusive, each of the names that appears in the seventh office line appears twice on the same party row in the office lines 8 to 13 inclusive, and in connection with each of such names the ballot label indicates one vote, and in that part of the group the voter can vote one or two votes for any one candidate, and as will be seen later on, he can cast three votes therein as well for two or three candidates in all. Office lines 14, 15, and 16 are devoted to another sub-group, in which sub-group the names that appear on the seventh office line appear but once, and in this sub-group the ballot label indicates one and one-half votes for each name. In the 17th, 18th, and 19th office lines each of the names on the seventh office line appears again but once, each name in a separate ballot space, as is true of all of the sub-groups except that on the seventh office line, and in this sub-group each ballot label indicates three votes for its candidate.

In determining the vote which must be credited to each candidate, the vote which the candidate has received in each of the sub-groups must be separately estimated by multiplying the number indicated by the counter by the factor which appears under his name on the ballot label, and the sum of all the votes thus ascertained must be taken as the total vote with which the candidates should be credited.

In my invention the various parts of the machine, especially the interlocking mechanism, are all designed to contribute accurately to the result above described, so that the machine cannot be voted on by any voters, so as to make it record a vote that will be in excess of the vote which the voter is entitled by law to cast.

Having thus described in a general way what the result is that must be secured, I will now describe the mechanism by which this result is secured.

In Fig. 1 I have shown a partial elevation of the keyboard of the machine including four party rows of keys extending from office line 7 to 19 inclusive. These keys are regularly interlocked in the manner described in my prior Patent No. 793,666. Reference numeral 1 refers to these keys. To each of these keys is connected an interlocking strap 6, which interlocking strap passes between interlocking rollers 3—3, which interlocking rollers are recessed so that between consecutive rollers a pair of interlocking straps is included. These rollers are carried by the interlocking channel 2.

As shown in Fig. 2, grouping pins 4, 4, are shown holding the pin rollers in place, 40 said pins marking the ends of the four sub-groups into which the office lines 7 to 19 inclusive are divided, there being five of these grouping pins in all for the assembly group.

The first office line, or sub-group, is referred 45 to as X^1 and embraces the office line No. 7.

The second of these sub-groups is referred to as X^2 and embraces office lines 8 to 13 inclusive. The third of these sub-groups is referred to as X^3 and embraces office lines 50 14, 15, and 16. The fourth of these sub-groups is referred to as X^4 , and embraces office lines 17, 18, and 19. An inspection of the interlock shown at sub-group X^1 in Fig. 2 shows that but one wedge can be pulled 55 into voted position; accordingly, on the seventh office line but one key can be voted.

In the sub-group X^2 three keys can be voted. In the sub-group X^3 two keys can be voted. In the sub-group X^4 one key 60 can be voted, the interlock in Fig. 2 being shown in each group with the corresponding number of open spaces into which the correct number of wedges can be pulled, and no more. In the sub-group X^2 in Fig. 65 2 three compensators 5 are shown. In the

sub-group X^3 but one compensator 5 is shown, and in the sub-group X^4 two compensators 5 are shown. These compensators take up space that might otherwise be occupied by wedges, and by their use the number of keys that can be voted in each sub-group is limited to the proper number. So far as anything shown in Figs. 1 or 2 is concerned, one key can be voted in sub-group X^1 , three keys in sub-group X^2 , two keys in sub-group X^3 , and one key in sub-group X^4 , and all of these can be in voted position at the same time, and if this were possible in the general operation of the machine, it would allow a voter to cast four 75 times as many votes as he is entitled to cast, which would be manifestly improper, and additional mechanism must be provided to limit each voter to the proper number, and this mechanism I am now about to describe.

As shown in Fig. 4 each of the interlocking straps 6 is provided with a shoulder 7 thereon. Mounted on the bottom of the machine at suitable intervals are the standards 8, 8; supported by these standards 80 are the rods 9, which supports the boosting bar in the machine, and which does not constitute any necessary part of my present invention, and the rods 10 and 11 by which the cumulative vote lockout is supported, 85 which lockout I will presently describe. These rods 9, 10, and 11 extend throughout the entire length of the machine, although if the location of the assembly group is known with sufficient definiteness it may 90 not be necessary for the rods 10 and 11 to extend but part way through the machine. The rods 10 and 11 are fastened to the standard 8, 8, by means of pins 12, which pass through the rods 10 and 11 but leave the 95 cylindrical surface of the rods unbroken on one side, so as not to interfere with the sliding of the cumulative lockout thereon, as it may be necessary to shift its position 100 from time to time.

As shown in Fig. 3 the cumulative lockout consists of a separate structure having the brackets 13, 13, therein connected by the tie-rod 14 near the bottom, and the interlocking channel 15 near the top. Supported in these brackets 13—13 is the shaft 16, which extends through the whole length of the structure, and has its bearings in the brackets 13. On this shaft at suitable intervals are keyed the cams 17, 17, so that the shaft and all of its cams will rotate together. At the top of these brackets 13—13 is mounted the shaft 19, on which is pivoted a plate 20 having the width of one office line, plate 21 having the width of 115 six office lines, plate 22 having the width of three office lines, and the plate 23 having the width of three office lines. The plates 20, 21, 22, and 23 coördinate with the parts in sub-groups X^1 , X^2 , X^3 , and X^4 respec- 120 125 130

tively. These plates are mounted to independently rotate on the shaft 19, which shaft is common to all of said plates. Each of these plates has connected thereto by a chain or other suitable connection 30, one or more cams 17 mounted on the shaft 16 below it, in consequence of which when any one of these plates and its cams 17 are lifted, the rock shaft 16 is rotated thereby, 10 and all of the cams 17-17 are lifted. This rock shaft extends continuously throughout the whole structure of the cumulative vote lockout. On this shaft 16 two of the cams 17-17 are provided for each of the plates 15 except plate 20. As the plate 20 is a very short one it will be seen presently that but one cam is sufficient for that plate for the purpose for which the cams are intended. Carried on each of the plates 20, 21, 22, and 20 23 is a pin 24, on which is pivoted pendants 25. Each of these pendants has thereon about midway of its length, an interlocking wedge 26, and a little below the wedge 26 and at right angles thereto is another interlocking wedge 27. The interlocking wedge 26 coöperates with the interlocking blocks 28 in the channel 15. The displacement of this wedge on the pendant 25 connected to the plate 20 is double that of any 30 of the other pendants, so that the displacement of the one pendant connected with plate 20 will equal the displacement of the two pendants connected to each of the other plates 21, 22, and 23. At the bottom of 35 each of these pendants is carried the interlocking roller 29, which interlocking roller 29 is intended to and does coöperate with the cam surface 17 under certain conditions and for particular purposes that will now 40 be described.

When, for example, the plate 21 is lifted, it will raise the two cams 17 connected therewith through the connections 30-30. It will also raise the interlocking rollers 29, 45 which are connected thereto so that no interlock will occur between the rollers 29 attached to the plate and the cam 17 with which they are normally in engagement. The cams 17, however, are all keyed to the shaft 16, and when the cams of any one plate are lifted it causes the lifting of the cams of the other plates as well, but it does not cause the lifting of the other plates as well, for as is shown in Fig. 4 the connection 50 30 has a sliding engagement with the plate with which it is connected, so that it can rise a limited distance independent thereof. As above described, it will be seen that there are seven cams keyed on this shaft 16, all of which will rock with it when any one or two of the cams are lifted, but as these cams may be raised a limited distance without disturbing the plates with which they are connected, it will be seen 60 that the raising of one of the plates a dis-

tance sufficient to permit the voting of the keys controlled thereby will not in any way cause the raising of the others. The interlocking channel 15 with the blocks 28 therein is provided to prevent the lifting of more than one of these plates at a time. The wedges 26 are so arranged with reference to the blocks 28 that when one of the plates is lifted all of the available room in the interlocking channel 15 is taken up, so that the other plates may not be lifted. In this way the lifting of more than one plate at a time is prevented. It has been found on trial that if the interlocking channel 15 with its blocks 28 is alone depended on to interlock the plates 20, 21, 22, and 23, that such plates will not return freely when the machine is reset, but will stick if the voter has attempted to lift two of those plates. This is due to the friction of the interlocking wedges 26 with the interlocking blocks 28 of the channel 15. This friction may be developed if the voter first votes keys in one of the sub-groups, and then tries to force to voted position a key in another of the sub-groups. This friction could be overcome by positively releasing the blocks on the resetting of the machine or by positively resetting the plates, but the cams 17 on the interlocking rollers 29 are provided so that this release may be depended upon to effect itself by gravity, so as to prevent the parts from sticking under any circumstances.

When one of the plates has been raised the interlocking blocks 28 have been closed in around the pendants 25, so as to prevent any movement of them along the channel 15. The cams 17 have been raised so as to swing outwardly all of the pendants 25 that are attached to the plates that have not been raised. In this position the interlocking wedges 27 of the pendants 25 that have not been raised are just about to engage with the lower edge of the interlocking channel 15 and in the upward movement of any of these plates after the cams 17 have been raised the wedges 27 will contact with the interlocking channel 15 before the wedges 26 can contact with the interlocking blocks 28, thus causing the jam or friction on the pendants 25 to come between the wedges 27 and the interlocking channel, and not between the wedges 26 and the blocks 28. For the purpose of this interlock the 105 cams 17 and the rollers 29 take the place of the other side of the interlocking channel. The wedges 26 and 27 are so positioned that when the pendants 25 are held out by the cams 17 pressing against the rollers 29, the 110 wedge 27 will engage with the channel before the wedge 26 can engage with the blocks. The lower end of the pendant 25 has the roller 29 thereon bearing against the cam surface 17 over which it rolls freely, 115 120 125 130

so that the cams 17 can travel past the roller 29 with little or no friction, and while the interlocking parts may tend to stick at the interlocking channel, they will 5 be promptly released as soon as the cam 17 has passed the interlocking roller, for then the interlocking parts can swing free again at the interlocking channel. The interlocking wedges 26 of the plate that has been 10 raised cannot be jammed against the interlocking blocks 28 by any attempt to raise either of the other plates, because the attempt to raise such other plates will in every case cause the jam to come locally between 15 the wedges 27 of their pendants 25, and the side of the interlocking channel. Neither can the interlocking wedges 27 of the plate that has been raised be jammed against the interlocking channel, because it has been 20 lifted high enough so that the rollers 29 thereon will be above the cams 17, and will not be operated thereby and because the openings in the channel are wider at such points than the wedges 27 at their widest 25 parts. This jam or friction between the wedges 27 and the channel occurs before the jam can occur with the wedge 26, so that no stress will be applied to the interlocking blocks 28 thereby. To assist the return of 30 the shaft 16 with the cams 17 thereon, I place on the said shaft a torsion spring 31, which spring tends to rotate such shaft so as to pull the cams down and release the rollers 29 and the interlocking wedges 27. 35 The interlocking channel in this case may be made of a single piece of metal with a T-shaped groove cut therein. At those places where the pendants 25 pass through the bottom channel 15, I cut holes through the bottom 40 of the channel of sufficient size to allow said pendants to travel up or down or sideways in either direction, as far as may be necessary to secure the proper working of the parts. It is not necessary that the interlocking channel 15 have an opening running clear through the top and bottom of it, as the interlocking pendants are few in number compared to the length of the channel and have a very limited movement. 45 A description of the operation of this cumulative vote lockout in the ordinary process of voting will now be given.

Referring to Figs. 4 and 5, it will be seen that when any one of the interlocking straps 55 6 is raised, due to the voting of its key 1, the said strap will, through its lug, or shoulder 7, raise the plate 20, 21, 22, or 23, that may be engaged therewith. This plate will in turn interlock with the other plates in 60 the manner above described, so that neither of the other plates can be raised, and this will in turn hold down the interlocking straps and keys that engage with such other plates. The engagement between the plates 65 and their respective straps will be under-

stood by comparing Figs. 2 and 3. The voting devices of the assembled group are divided into four sub-groups by the grouping pins 4, 4, and by means of the plates 20, 21, 22, and 23. When the voter has started 70 to vote in one of these sub-groups, he is prevented from voting in any of the other sub-groups. If he has made a mistake by starting in the wrong sub-group, the resetting of the voted keys in that sub-group will 75 restore the plate 20, 21, 22, or 23 to its initial position, thus permitting the voter to start over again in another group, but it is apparent that with this arrangement of the parts, that the voter will not find it possible 80 to have keys voted in two sub-groups at the same time.

In different elections it may be necessary to connect this attachment to different office lines on the machine. Fig. 1 shows the assembly group extending from the seventh office line to the nineteenth inclusive. It might, however, in another election begin with the fifteenth office line and extend to the twenty-seventh. On this account I have 90 made this lockout adjustable so as to connect it with those office lines where the assembly ticket may happen to come on the machine. As shown in Fig. 4 this attachment has a sliding engagement with the 95 rods 10 and 11, and this attachment may be clamped to such rods in any position by means of the clamps 32, which have a frictional engagement with the rods 10 and 11, and which are positively fastened to the 100 brackets 13 by means of the screw 33. By these connections the attachment can be readily fastened in any position and moved from one position to another. The interlocking channel 2-2 and its rollers is made 105 interchangeable throughout the whole machine, so that single and multicandidate groups can be formed at any place.

On each side of each of the plates 20, 21, 22, and 23 I provide the fingers 34, which 110 fingers pass between and separate the end interlocking straps 6 of the sub-groups, so that said interlocking straps 6 will be positively held in engagement with the plates 20, 21, 22, and 23 belonging to that particular sub-group, so that such interlocking straps cannot become accidentally engaged with the plate belonging to another sub-group. These fingers 34 are each provided with a lug which prevents them from getting 120 below the plate on which they are mounted, but which does not interfere with their being raised above the plate on which they are pivoted.

The surplus space in the interlocking 125 channel 15 is taken up by compensators 5-5 in the manner shown in Fig. 2. A detail of one of these compensators is shown in Fig. 12, and in Fig. 6 a compensator is shown inserted between the two straps and 130

their wedges which are inclosed between two consecutive rollers 3.

When the assembly group is voted on the machine in the manner above described, it is necessary to have in each party line the key of the first office line of the group connected to its straight ticket voting mechanism, while the keys of the other office lines of the group must be disconnected 5 from their straight ticket voting mechanisms so as not to be operated thereby, or so that such keys in turn will not interfere with the operation of the straight ticket voting mechanism. The construction and 10 operation of the parts by which this result is secured are shown in Figs. 8 to 11 inclusive, and these parts I am now about to describe.

In Fig. 8 the crank 40 of the straight ticket key is shown in dotted lines. When the party lever is operated the crank 40 will move the connecting link 41 and pull to the right the straight ticket bar 42. On this straight ticket bar is pivoted a series of 15 latches 43, one latch at each office line. This latch can be raised and when in raised position it will engage with the lug 44 on the key 1, when the straight ticket bar moves forward, or it can be lowered, in which 20 case it will not engage with the lug 44 and will not operate the key 1 when the straight ticket bar is operated. All of these latches 43 of one office line are connected to a slide 25 47. This slide 47 has slots 45 cut therein at suitable intervals, with which slot 45 engages studs 46 carried on the latches 43. Each of these slots are somewhat longer than the travel of the straight ticket bar 42 plus the diameter of one of the studs 46. 30 By raising the slide 47 all of the latches 43 of that office line will be thrown into position to engage with their respective keys and to move them to voted position when their straight ticket bars are operated, and 35 40 when the slides 47 are lowered the latches 43 will not engage with their respective keys and will not move them, and if the keys are locked against movement for any reason, as for example, by the plates 21, 22, 45 50 and 23, the operation of the straight ticket keys will not be interfered with. Referring to Figs. 2 and 3 it will be seen that, of the six office lines of keys connected to plate 21 but three keys can be voted, and that in the 55 60 three office lines connected to plate 2 but two keys can be voted: and that in the three office lines connected to plate 23, but one key can be voted, hence unless it were possible to disconnect office lines of keys in each 65 70 group in excess of this number from the straight ticket mechanism, it would be impossible to operate the straight ticket voting mechanism when the assembly group occurred on the machine. Because of the 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 10

with said lugs, one for each group, and each plate being supported so as to be lifted when any interlocking strap in its group is operated, and means to prevent the lifting of the remaining plates when any one of them has been lifted.

4. The combination in a voting machine of interlocking straps, each strap having a lug thereon, said straps being divided into 10 groups, a shaft extending parallel to said groups of straps, plates pivotally mounted on said shaft one for each group of straps, each plate engaging with the lugs on the straps of its particular group, so as to be 15 lifted thereby when any strap in its group is operated, means to prevent the lifting of the remaining plates when any one of them has been lifted.

5. The combination in a voting machine 20 of keys interlocked in a plurality of groups, means for interlocking each of said groups against all the remaining groups, so as to permit the voting of keys in any one of said groups and prevent the voting of keys in 25 the remaining groups, said means being movably mounted to engage with groups of keys formed in any part of the machine.

6. A voting machine interlock comprising a series of plates pivotally mounted on a 30 single shaft and interlocked to prevent the lifting of more than one thereof at a time, brackets supporting said shaft, supports for said brackets, said brackets being mounted on said supports so as to be moved along 35 said supports.

7. A voting machine interlock comprising a series of plates pivotally mounted on a single shaft and interlocked to prevent the lifting of more than one thereof at a time, 40 brackets supporting said shaft, supports for said brackets, said brackets being mounted on said supports so as to be moved along said supports and clamped thereto.

8. A voting machine interlock comprising 45 a series of plates pivotally mounted, an interlock therefor comprising wedges and blocks to prevent the lifting of more than one of said plates at a time, an additional lockout therefor to prevent any strain being 50 put on the interlocking blocks by the attempted operation of plates successively.

9. A voting machine interlock comprising a series of plates pivotally mounted, an interlock therefor comprising wedges and blocks 55 to prevent the lifting of more than one of said plates at a time, a lockout therefor, said lockout comprising pendants having enlargements thereon, an obstruction with which said enlargements can engage, one or 60 more of said pendants being separately attached to each plate, a shaft having cams thereon connected to all the plates and rocked by the lifting of any one of said plates, said cams engaging with the pendants 65 when the shaft is rocked, to move said

pendants to engage said enlargements with said obstruction to prevent the longitudinal movement of said pendants or the movement of the plates connected thereto.

10. A voting machine interlock comprising 70 a series of plates, a cam shaft connected to said plates and operated by any one of said plates, one or more interlocking wedges connected to each plate, an interlocking channel and blocks for said wedges, one or more of said wedges being moved to interlocking position by the plate connected thereto, the remaining wedges being moved along the channel by the operated wedge or wedges and across the channel by the cam shaft.

11. An interlocking wedge composed of a 75 stem having two wedges placed thereon at right angles to each other and a channel having blocks therein with which said wedges engage, one of said wedges interlocking with the channel and the other wedge interlocking with the block.

12. An interlocking wedge composed of a 80 stem having two wedges placed thereon in series and at right angles to each other and a channel having blocks therein with which said wedges engage, one of said wedges interlocking with the channel and the other wedge interlocking with the block.

13. The combination in a voting machine 85 of interlocking straps each having a lug thereon, said straps being divided into groups, a pivoted plate engaging the lugs of the straps of one group, said plate being supported so as to be lifted when any strap of 90 its group is operated, fingers mounted on said plate and projecting beyond it to engage the straps of the group and hold them in engagement with the plate.

14. A compensator for a voting machine 95 interlock consisting of an L shaped piece of metal, one of its arms adapted to be engaged with the wedges or blocks of the interlocking channel, and the other of its arms adapted to overhang said channel and be supported thereby.

15. A voting machine interlock consisting 105 of a channel, wedges and blocks, a compensator therefor consisting of an L shaped piece of metal, one of its arms being adapted to engage with the wedges or blocks, and the other of its arms adapted to overhang the channel and be supported thereby.

16. The combination in a voting machine 110 of keys arranged in a plurality of office lines, interlocking straps connected to said keys, shoulders on said straps, a frame having a plurality of wings thereon, capable between them of engaging the interlocking straps of 115 a plurality of consecutive office lines, said frame being adjustably mounted to be shifted into engagement with different combinations of said interlocking straps.

17. The combination in a voting machine 120

of keys arranged in a plurality of office lines, interlocking straps connected to said keys, shoulders on said straps, a frame having a plurality of wings thereon, capable between them of engaging the interlocking straps of a plurality of consecutive office lines, said frame being adjustably mounted to be shifted into engagement with different combinations of said interlocking straps, interlocking devices between said wings to prevent the operation of more than one thereof whereby the voting of the keys is correspondingly limited.

18. The combination in a voting machine of a key, a party bar movable to operate the key, a latch pivoted on the party bar and capable of being elevated or depressed, said latch in its elevated position being capable of engagement with the key to operate it on the movement of the bar, said latch in its depressed position being incapable of engagement with the key to operate it on the movement of the bar and means for each office line for operating all the latches thereof collectively.

19. The combination in a voting machine of a key, a party bar movable to operate the key, a latch pivoted on the party bar and capable of being elevated or depressed, said latch in its elevated position being capable of engagement with the key to operate it on the movement of the bar, said latch in its depressed position being incapable of engagement with the key to operate it on the movement of the bar, and means for positively holding the latch in either position.

20. The combination in a voting machine of a key, a party bar movable to operate the key, a latch pivoted on the party bar and capable of being elevated or depressed, said latch in its elevated position being capable of engagement with the key to operate it on the movement of the bar, said latch in its depressed position being incapable of engagement with the key to operate it on the movement of the bar, and means mounted on the frame of the machine independent of the straight ticket mechanism for positively holding the latch in either position, said means being external to the party bar and without interfering with the movement thereof.

21. The combination in a voting machine of keys arranged in parallel party lines and

in office rows transverse thereto, a party bar 55 for operating collectively the keys in a party row, latches pivoted on said bars one for each key, through which latches the bar operates the keys, said latches being capable of being engaged with or disengaged from their respective keys, to operate said keys or leave them idle on the operation of the bar and means for each office line for operating all the latches thereof collectively.

22. The combination in a voting machine 65 of keys arranged in parallel party lines and in office rows transverse thereto, a party bar for operating collectively the keys in a party row, latches pivoted on said bars one for each key, through which latches the bar operates the keys, said latches being capable of being engaged with or disengaged from their respective keys, to operate said keys or leave them idle on the operation of the bar, a slide engaged with the latches belonging to 70 all the keys of an office line, said slide being movable with the latches to connect or disconnect all the party bars from their respective keys of its office line.

23. The combination in a voting machine 80 of a key, a party bar movable to operate the key, a latch pivoted on the party bar and capable of engagement with or disengagement from the key, a stud on said latch, a slide having a slot therein, a stud on the 85 latch engaged with said slot and movable therein, said slide being movable to engage or disengage the latch with its key, said latch being operable by the party bar while in either position while maintaining engagement with the slide.

24. In a voting machine, an interlocking wedge composed of a stem having two wedges placed thereon at right angles to each other, and separate devices with which 95 each of said wedges interlock.

25. An interlocking wedge composed of a stem having two wedges placed thereon in series and at right angles to each other, and separate devices with which each of said 100 wedges interlock.

In testimony whereof I affix my signature in presence of two witnesses.

WILLIAM J. LAUSTERER.
